UNITED STATES PATENT OFFICE.

GEORGE W. WALTERS, OF DEER LODGE, MONTANA TERRITORY.

GATE.

SPECIFICATION forming part of Letters Patent No. 351,141, dated October 19, 1886.

Application filed June 18, 1886. Serial No. 205,544. (Model.)

To all whom it may concern:

Be it known that I, GEORGE W. WALTERS, of Deer Lodge, in the county of Deer Lodge and Territory of Montana, have invented a 5 new and Improved Gate, of which the following is a full, clear, and exact description.

My invention relates to gates of that class which are lifted and slid across the roadway, and are operated by hinged lifting-bars, which 10 in turn are operated by pulling on cords attached to overhead levers to which the gate-lifting bars are connected; and the invention has for its object to provide a simple, inexpensive, substantial, and efficient gate of this 15 character, which may be operated with certainty and with little effort on the part of a person in a vehicle or on horseback.

The invention consists in certain novel features of construction and combinations of parts 20 of the gate, all as hereinafter fully described and claimed.

Reference is to be had to the accompanying drawings, forming a part of this specification, in which similar letters of reference indicate 25 corresponding parts in all the figures.

Figure 1 is a side elevation of my improved gate, partly broken away, and shows the gate closed in full lines and open in dotted lines. Fig. 2 is a plan view of the gate-frame and 30 gate, the gate being shown open. Fig. 3 is a detail perspective view of parts of the gate-operating mechanism, and Fig. 4 is a detail sectional view of parts of the gate on the line x x in Fig. 1.

To a heavy sill-timber, A, are secured the lower ends of an outer broad post, B, and two inner smaller posts, C C, which latter posts are connected by a cross-bar, D, to which and the upper end of the post B a head-beam, E, is 40 fixed. Diagonally-ranging braces strengthen the head portion of the gate-frame. A cross-sill timber, A', is let into the under side of the sill A, and is stayed to the opposite posts C C by inclined braces a' a', whereby lateral stiffness is given the gate-frame.

The outer bar or upright, f, of the gate proper, F, extends upward, and at its forked extremity carries a roller, g, which runs on a 45 rod, G, fastened at opposite ends in the post and bar B D of the gate-frame. The body part

of the gate F may have any approved construction. It is shown made of end and center uprights, rails, and diagonal braces, and the lower rail, f', projects at opposite ends of the gate to enter a slot, b, made in the outer post, 55 B, and to stand between blocks c c, fixed to the opposing faces of the inner posts, C C, whereby the gate is steadied laterally at the bottom.

Lifting bars or levers H H are strongly hinged at their lower ends, as at h, to a cross-bar or block, I, fixed to the sill A, and range upward, one at each side of the gate F, and are rigidly connected at their tops above the upper rail of the gate by a block, H', in which is fastened an eyebolt, J, the eye of which is 60 linked to the eye of a similar bolt, K, fastened in the gate-rail f''. When the gate is closed, these bars H H extend outward diagonally and fit between the beveled upper ends of the post-blocks c c, as shown in Fig. 4, thereby aiding 65 the outer bar, f, of the gate, which incloses the guide-rod G, in preventing a lateral play of the upper part of the gate F. Short posts or pins L L are set into the sill A or into a timber, a', 70 fixed thereto, so as to stand one at each side 75 of the lower rail of the closed gate and serve as guides to the gate as it is being opened or closed. The gate when closed rests upon a buffer, l, and when open rests upon a buffer, l'. Said buffers are shown fixed to the sill A, and 80 may be made of rubber or other suitable material to deaden the noise and relieve the shocks of the fall of the gate.

In opposite ends of the gate-frame bar D there are fixed eyebolts m m, to which are ful-crumed, by eye bolts m' m', fixed in them, the gate-operating levers M M, the outer ends of 85 which extend a sufficient distance along the roadway, at opposite sides of the gate F, to allow pull-cords m² on the levers to be drawn 90 upon by a person on horseback or in a vehicle for opening and closing the gate without dismounting or alighting. The inner or back ends of the levers are crossed and bolted together at m³. To one of the levers there is attached the upper end of a rod, N, the lower end of which is connected loosely by an eye, n, with the cranked portion o of a trip-arm, O, which is journaled at one side of the crank o in a metal yoke, P, bolted by its ears p to one 95 100

of the gate-lifting levers H, and at the other side of the crank in said lever H, or, preferably, in a metal plate, R, fastened to the lever, there are formed stops r', r'' , against which the crank 5 o strikes to limit the throw of the trip-arm in either direction. The stem o' of the trip-arm O extends beyond the axis of the arm and about in the plane of the arm-crank o for a sufficient distance to strike either of two pins, S 10 T, which are fixed in a horizontal bar, U, supported at opposite ends by one of the gate frame-posts C and by a short post, V, fixed to the sill A.

The operation is as follows: We will suppose the gate is closed, as in Fig. 1. The arm O then stands in the inclined position shown, and the crank o of the arm will be swung outward against the stop r on the lifting-bar H. Should either of the cords m^2 be pulled to 15 operate the levers M M and draw the rod N upward, the lower end or eye, n, of the rod will draw on the cross piece or bar of the crank o, which, by action on the stop r, will swing the lifting-bars H over on the hinges h, and 20 thereby lift the back end of the gate F and partly open the gate, the roller g meanwhile supporting the forward end of the gate from the rod G and relieving the bars H of about half the weight of the gate, thereby making it 25 quite easy for a person to operate the gate, as a comparatively light pull only is required on the cord m^2 . As the gate is thrown past its dead-center of movement by the pull on the lever, the pull-cord is slackened or released 30 and the weight and momentum of the gate will carry it to full open position. About the time the gate passes its center of movement the stem o' of the trip-arm O will strike the pin T to reverse the crank o and carry its wrist backward 35 until the crank strikes the stop r' on the lifting-bar H about the time the back end of the gate swings down onto buffer l', leaving the crank in position for the next pull on it to close the gate. To close the gate, one of the lever-cords 40 45 m² will be pulled and the bars H will be raised with the back end of the gate by lift of the trip-arm crank o on the stop r' of the lifting-bar, and as the gate passes the center by its momentum, the stem o' of the trip-arm will 50 strike the pin S, again reversing the position of the crank and swinging it forward or outward until the crank again strikes the stop r as the gate closes, to bring the crank-arm to the required position for the next pull on it 55 by the lever to open the gate. In closing the gate the roller g and guide-rod G relieve the lifting-bars and the operator of the weight of the gate, as when opening the gate as above described.

6c The rigid connection of the ends of the lifting-bars H H, by means of the block H', bolted securely to and between the bars, allows operation of the gate by a single rod, N, connected to one of the bars H and to the levers M, and 65 also prevents any side strain on the gate in

opening and closing it, and the eyebolt-connections of the gate and lifting-bars allow lifting and swinging of the back end of the gate with very little friction.

The guide-pins L L offer little or no obstruction to travel over the roadway which the gate-frame spans. The uprights of the frame may be set firmly into the ground and the sills A A' be dispensed with; but when the sills are used they will usually be covered with earth, leaving the top of the sill-timber a² about level with the ground surface.

Having thus fully described my invention, I claim as new and desire to secure by Letters Patent—

1. The combination, with the gate-frame, of a horizontal guide-rod held thereby, the gate proper having an outer bar hung upon the guide-rod, and lifting-bars hinged at their lower ends to a ground-support and connected 85 at their upper ends with the gate, and means for operating said bars, substantially as shown and described, whereby as the lifting-bars and gate are operated part of the weight of the gate will be borne by the overhead guide-rod, as 90 set forth.

2. The combination, with the gate-frame, a horizontal rod, G, thereon, the gate F, having an outer bar, f, hung on rod G, lifting-bars H H, hinged at h to a ground support and connected rigidly at their tops by a block, H', and suitable fastenings, overhead operating-levers M M, fulcrumed to the gate-frame and extending one at each side of the gate over the roadway and connected at their inner ends, as at 100 m^3 , and a rod connecting the lifting-bars with the operating-levers, substantially as described, for the purposes set forth.

3. The combination, with the gate F and a lifting-bar, as at H, hinged to a ground-support attached at its upper end to the gate, and provided with stops r', r'' , substantially as specified, and means for operating said bar, of a trip-arm, O, formed with a crank, o, and stem o', and journaled on the bar H, and trip-pins S T, positioned for contact of the trip-arm with them, substantially as described, for the purposes set forth.

4. In combination, the gate F, a lifting-bar, as at H, hinged to a ground-support and attached at its upper end to the gate, and provided with stops r', r'' , a trip-arm, O, having a crank, o, and stem o', and journaled on the bar H, trip-pins S T, positioned for contact of the arm O with them, and a pull-rod, N, connected to the cross-bar of the crank o and to operating-levers, substantially as described, for the purposes set forth.

5. A device for throwing a lifting and sliding gate past its dead-center of movement, 125 combining a cranked trip-arm, a bar to which said arm is journaled and by which the gate is directly moved, an operating-rod connected to the crank of said trip-arm, fixed trip-pins and stops applied to said gate-operating bar, said 130

trip-arm having a stem for contact with the said pins, substantially as and for the purpose specified.

6. A device for throwing a lifting and sliding gate past its dead-center of movement, combining a cranked trip-arm having a stem, an operating-rod connected to the crank of said trip-arm, fixed trip-pins having contact with said stem, the gate operating or lifting

bar having a yoke, in which bar and yoke the trip-arm is journaled, and stops applied to said lifting-bar, substantially as and for the purpose set forth.
